UNITED STATES PATENT OFFICE.

STUART J. CLARK, OF AUBURN, ILLINOIS, ASSIGNOR OF ONE-HALF TO AUGUST EPLEY,
OF AUBURN, ILLINOIS.

FOLDING UMBRELLA.

1,121,977.

Specification of Letters Patent. Patented Dec. 22, 1914.

Application filed October 16, 1912. Serial No. 726,116.

To all whom it may concern:

Be it known that I, STUART J. CLARK, a citizen of the United States, residing at Auburn, in the county of Sangamon and State 5 of Illinois, have invented new and useful Improvements in Folding Umbrellas, of which the following is a specification.

The invention relates to umbrellas of the class which are adapted to be folded to occupy short space for convenience in packing 10 in a trunk or handbag.

This invention is a modification and improvement of the invention set forth in United States Patent No. 973,406, folding 15 umbrella, granted to me October 18, 1910.

The purpose of this invention is to provide in connection with a hinged staff, a sleeve adapted to slide on the staff and within which the staff may be partially rotated, 20 and adapted to cover and conceal the hinge of the staff and likewise adapted to control the movement of the ribs and braces during the raising, lowering, or folding of the umbrella.

25 The invention is illustrated in the annexed drawing to which reference is hereby made and is hereinafter particularly described and finally recited in the appended claim.

Figure 1 is an enlarged broken elevation, 30 partly in section, of the staff, the sleeve, and the clutch for effecting partial rotation of the staff within the sleeve. Fig. 2 is an enlarged developed plan of part of the sleeve and the clutch and shows in dotted lines the 35 sleeve disengaged from and raised slightly above the clutch.

Similar reference numerals designate like parts in both views.

The staff 1 is preferably a metal rod of 40 suitable dimensions.

A pedestal 4 is secured on a handle 5 and has at its upper end a circular rim 4^a. It also has a central bore 4^b accommodating the lower end of the staff 1 so that the staff may 45 rotate in the bore.

The clutch member 6 is secured on the staff 1 by a transverse pin 1^a. The lower staff-member is adapted to rotate in the hole 4^b in the pedestal 4, and the hole 5^a in the 50 handle 5. The clutch-member 6 has a central chamber 6^a accommodating a spring 7. It also has an internal circular channel 6^c in which the circular rim 4^a of the pedestal fits loosely so that the clutch may be turned 55 on the rim of the pedestal and the rim will

prevent longitudinal movement of the clutch. The clutch also has a notch 6^b accommodating a tooth 8^a on the sleeve 8.

A helical spring 7 surrounds the staff within the chamber 6^a. One end of the 60 spring is connected with the clutch 6 and the other end is connected with the pedestal 4, and the spring is effective to rotate the clutch as hereinafter described.

The sleeve 8 surrounds the staff 1 and has 65 a tooth 8^a adapted to enter the notch 6^b in the clutch 6. The inclined lower end of the sleeve conforms to the inclined upper end of the clutch so that if the sleeve be gripped in the hand to keep it from turning and the 70 clutch be turned, the inclined upper surface of the clutch will slide on the inclined lower surface of the sleeve.

When the tooth 8^a is retracted from the notch 6^b the sleeve may be slid upward on 75 the staff. When the tooth is in the notch it will prevent upward sliding of the sleeve.

The staff 1 is in two parts connected by a suitable hinge 20. When the sleeve is depressed the hinge 20 is within the sleeve and 80 the sleeve keeps the staff rigid. If the sleeve be slid upward above the hinge 20 the hinge will be free to turn so that the lower staff-member and connected parts may be folded to occupy a position approximately 85 parallel to the upper staff-member.

To fold the umbrella handle the sleeve 8 will be grasped in one hand and the clutch 6 will be rotated with the other hand to withdraw the tooth 8^a from the 90 notch 6^b and the sleeve will then be pushed upward to uncover the hinge. The lower member of the staff will then be turned upward on its hinge to complete the folding of the umbrella handle. 95

Having fully described my invention what I claim as new and desire to secure by Letters Patent is:

In a folding umbrella, the combination of a handle; a pedestal stationary on the handle and having a circular rim and a central bore; a hinged staff rotative in the bore of the pedestal; a chambered clutch rigidly connected with the staff and rotative on the rim of the pedestal and having an inclined 100 end and a notch; a spring within the chamber of the clutch, adapted to be compressed by rotating the clutch in one direction and acting to rotate the clutch and the connected staff in the reverse direction; and a sleeve 105 110

normally covering the hinge of the staff and adapted to slide on the staff to uncover the hinge, and rotative on the rim of the pedestal and having an inclined end adapted to engage on the inclined end of the clutch and a tooth adapted to engage in the notch of the clutch.

Signed at Auburn, Illinois, this 20th day of April, 1912.

STUART J. CLARK.
